TOOTH BRUSH

George A. Bauler, Minneapolis, Minn.

Application April 24, 1937, Serial No. 138,795

1 Claim. (Cl. 15—176)

This invention relates to tooth brushes of a type which is particularly suited for use when traveling.

One of the objects of my invention is to provide a tooth brush construction which is conveniently made so that it can be carried in the pocket and also to provide a brush which has greater efficiency than the type of tooth brush in general use today. It is a brush so constructed that no matter how it is held in the hand it is always in position for brushing the teeth, since there is no top or bottom or right or wrong side of the brushing element itself.

Another object of the invention is to provide a brushing head which can be changed from one position to the other relative to the handle so that certain parts of the mouth can be more easily reached.

These and other objects and advantages will more fully appear from the following description made in connection with the accompanying drawing, wherein like reference characters refer to the same or similar parts throughout the views, and, in which:

Fig. 1 is a plan view with part of the handle and protective cap broken away;

Fig. 2 is a plan view with the cap removed and the head in one of its positions;

Fig. 3 is a plan view showing the head attached to the handle in a different position, and

Fig. 4 is a section taken on the line 4—4 of Fig. 3.

In the drawing, I have shown a handle 5 which is preferably of uniform cylindrical shape throughout most of its length. The top portion of the handle is tapered as at 6 and the extreme tip of the handle is provided with a threaded portion 7.

The brush head includes a relatively long narrow bristle-supporting base 8 to which a plurality of radiating bristles 9 are secured in any desired manner. The bristle-supporting element 8 can be made of a plastic material with the inner ends of the bristles embedded therein.

This bristle-supporting element is provided with a pair of threaded sockets 10 extending inwardly from the ends of the element and also with a threaded aperture 11 which extends transversely through the element at its center. Thus it will be seen that the brush head can be threadedly secured to the handle in either of the positions shown in the drawing, and it will be found that by changing the position of the head relative to the handle, it will be much easier to clean certain of the teeth which are difficult to reach with an ordinary brush. It should also be noted that, because of the bristles radiating from the base in the manner shown, there is provided a brush head which is cylindrical in shape and

which presents a substantially unbroken effective cleaning area throughout the entire brush head. In the conventional tooth brush, the bristles are secured to one side of a base element and the brush must be held in one particular position with respect to the teeth. It will be readily seen, however, that with my construction the brush head and handle are so formed that the brush is always in position for use and need not be twisted or otherwise manipulated to bring the bristles into proper contact with the teeth.

Toward the upper portion of the handle, I have provided a threaded area 12 for securing the cap 13 which is adapted to fit over the brush head when the head is secured in the positions shown in Figs. 1 and 2. This protective cap will keep the brush clean and will also permit placing of the brush in a suitcase or in the pockets of the user immediately after the brush has been used and before it has dried. A clip 14 may be provided to secure the article in the pocket and ventilating openings 15 are also preferred.

The main portion of the handle 5 is hollow to provide a chamber 16 for a small tube of tooth paste or for a supply of tooth powder. The lower end of the hollow handle is open and is provided with a removable threaded cap 17. The tapering upper portion 6 of the handle is provided so that the brush may be more easily inserted in the mouth, since the main portion of the handle is relatively large to provide sufficient space for the powder chamber 16.

From the foregoing, it will be seen that I have provided a simply constructed self-contained tooth cleaning device which may be clipped in the pocket of the user when not being used. The shape of the brush head and its adaptability to different positions with respect to the handle provide a device of greater efficiency without going into a complicated structure.

It will, of course, be understood that various changes may be made in the form, details, arrangement and proportions of the various parts without departing from the scope of my invention.

What is claimed is:

A tooth brush comprising a handle and a brush head, said head comprising a substantially cylindrical bristle base, and bristles extending radially equidistantly from said base throughout substantially its entire cylindrical surface area to provide a substantially unbroken cylindrical brushing surface, and said brush head being detachably secured to the end of said handle at right angles thereto, whereby surfaces of the teeth can be reached with portions of said bristles always lying in brushing position.
